AIR FILTER

Louis Spraggen, Bridgeport, Conn.

Application June 15, 1944, Serial No. 540,441

1 Claim. (Cl. 183—71)

1

This invention relates to air filters, and more particularly to a filtering unit attachable to air-sucking equipment such as pumps, internal combustion engines and the like to purify air being used by same.

Filters commonly used for this general purpose have screening elements which in some cases are made of woven or felt cloth, and in other cases are in the form of sponge-like pads made of metallic ribbon. In purifying air, the latter type are generally coated with a non-drying or viscous dust-collecting substance such as oil, whereas the cloth elements are usually operated dry, and depend on the closeness of the weave and the fibrous character of the material for cleaning the air.

In the case of filters employing metallic pads, the elements are formed by severing a predetermined amount of material from a large supply, and shaping the material usually into the form of an annulus, for insertion into a supporting housing. When this is done, the interstices of the material, which originally are not too uniform in size and shape due to the lack of resilience of the metallic ribbon and due to handling, are further deformed so that a considerable diverging exists when the element is finally resting in the filter. Moreover, at the point where the ends of the element meet, in an annulus, large irregular spaces are created, a condition which cannot be readily corrected.

As a result, incompletely filtered air is permitted to enter the equipment through the large openings and interstices of the irregular pad structure, and may under severe and adverse atmospheric conditions cause considerable damage.

Textile cloth or fabric filter elements generally obviate this condition, but are more costly to make, requiring especially constructed supporting structures and more expensive assembly operations. Also, the elements may not be readily cleaned, so that when they become dirty replacement with new elements is necessary. Whereas cleaning of the metallic sponge element of air filters may be accomplished in a simple manner by merely dipping them into a solvent and re-coating with fresh oil. This procedure would cause sagging and deterioration of the material if applied to a textile fabric air-filter element. Also, with textile fabric there is the likelihood of tearing or unraveling, which would defeat the purpose of the filter.

It is an object of the present invention to obviate the above disadvantages in filters. This is accomplished by the provision of a filtering

2

unit having comparatively rigid self-supporting screening elements which are non-deteriorating and provide numerous interstices substantially uniform in size and shape and also provide fibrous tendrils extending about and into the interstices to intercept and facilitate the collecting of foreign matter from the incoming air.

Due to the absence of inadvertent large openings either at or between junctures of the screening material, the cleaning of the air is accomplished uniformly and by the use of fibrous tendrils the dirt collecting surfaces and areas are greatly increased, and the filtering action generally improved.

15 The filter or screening elements may be used in a dry condition to filter air, or may be coated with a non-drying viscous substance such as oil, depending on requirements, and in either case cleaning of the elements may be carried out without detriment thereto by employing a simple rinsing procedure. The interstices of the elements may be accurately controlled as to size and uniformity, may be made small or large to suit particular conditions, and the elements themselves may be conveniently formed and interfitted if desired to provide consecutive screenings of the air.

20 In one form of the invention, the filter elements comprise formed pieces of wire mesh, the wires of which at their points of contact are bound together by cement, the mesh having a uniform coating of flock also secured by cement and arranged so that the fibers thereof extend from the wires in all directions. According to this arrangement the use of pieces of pliable textile fabric in a filter, with their accompanying disadvantages, is not necessary.

25 In an illustrated embodiment of this invention, the construction of the unit provides two such flocked elements, each cylindrical, one of larger diameter than the other, which are concentrically mounted in a housing, and a third element is zig-zag folded so that when the ends are connected it forms a multi-pointed star which may be disposed between the two cylindrical elements.

30 In another illustrated form of the invention a plurality of cylindrical concentrically disposed elements is carried in a holder.

35 In each of these constructions the air may pass through the elements consecutively, the outer one first.

40 According to the present invention rigid screening elements may be woven or molded plastic screening, formed of Vinylite or other plastic material, or may be made of expanded metal or

paper, formed papier-mâché, and the like, with the flock coating secured to the screen through the use of adhesives suitable to each particular material.

The end of the screen elements may be bound with a soft textile fabric so as to seal the same and housing plates between which the screen elements are located. Or a felt strip may be interwoven in the mesh, when the elements are being made so that when the mesh is cut to divide the felt strip, the cut edges of the mesh have felt edging which functions as a gasket at the points where the filter housing engages the edge of the screens. Also, the surfaces of the housing which engage and support the elements may be heavily coated with a yieldable material into which the edges of the mesh may be embedded, to provide an air-tight connection.

A novel supporting or housing structure provides for quick and convenient removal of the elements for cleaning purposes, yet prevents leakage past co-engaging surfaces. By this construction replacement of the elements may be quickly accomplished also.

Other features and advantages will hereinafter appear.

In the accompanying drawings—

Figure 1 is a top view of a filtering unit made according to the invention, with the top plate of the housing removed.

Fig. 2 is an axial section taken on the line 2—2 of Fig. 1, parts of the screens being shown diagrammatically.

Fig. 3 is a perspective view of the central supporting tube of the unit.

Fig. 4 is a perspective view of the top closure for the tube.

Fig. 5 is a perspective view of an end plate carrier for the star-shaped filter element.

Fig. 6 is a fragmentary elevational detail of the filter mesh construction, showing the large mesh employed in the outer cylindrical element of the filtering unit.

Fig. 7 is similar to Fig. 6, but shows the smaller mesh employed in the inner cylindrical element of the unit.

Fig. 8 is a perspective view of the zigzag folded mesh for the star-shaped intermediate element, before being expanded and formed to final shape.

Fig. 9 is an enlarged fragmentary sectional view of a folded edge of an element made according to the invention.

Fig. 10 is a top view of a modified form of filtering unit, with the top plate of the housing removed.

Fig. 11 is a top view of another modified form of filtering unit, top housing plate removed.

Fig. 12 is a side elevation, partly in section, of another modified form of filtering unit, for mounting with its axis horizontal.

Fig. 13 is a transverse section taken on the line 13—13 of Fig. 12.

Fig. 14 is a transverse section taken on the line 14—14 of Fig. 12.

The filtering unit shown in Figs. 1 through 9, which may be advantageously used to filter intake air for the carburetors of internal combustion engines, for pumps and the like, has a housing comprising a central tubular stem 20 which carries circular bottom and top plates 21 and 22, respectively. The bottom plate 21 has an upturned central flange 21a which snugly fits the outside diameter of the stem 20 and is spot welded thereto as indicated in Fig. 2.

The top end of the stem 20 is provided with a

formed sheet metal closure 23 which fits snugly inside the stem and is also spot welded thereto (Fig. 2). The closure 23 is at its center extruded and threaded to carry a stud 24 extending through the center of the top plate 22, a winged nut 25 being provided for demountably securing the top plate to the stem.

According to the invention the bottom and top plates 21 and 22 are shaped to carry the self-supporting filtering elements of the unit, and for this purpose as shown in Fig. 2 the peripheral edges of the plates have flanges 21b and 22a respectively, extending toward each other. Carried between the top and bottom plates in engagement with the flanges 21b and 22a is a novel comparatively rigid self-supporting filtering element 26. This element is of wire mesh having a coating of flock disposed on it in such a manner that the fibers thereof extend in all directions from the wires, forming dirt-collecting tendrils which effectively filter and clean air which may pass through the element. The flock may be deposited on the mesh by being blown against it, and made to adhere to the wires by a suitable adhesive or cement, which may also bind the wires themselves where they cross. As shown in Fig. 1 the flocked mesh is formed into a cylinder which fits closely inside and against the flanges 21b and 22a of the top and bottom plates, the joining edges of the cylinder being secured by a clamp strip 26a having lanced fingers 26b which pass through the interstices of the mesh and are folded over on the latter at the inside. The filtering element 26 as thus constructed is substantially rigid so that it may be firmly held between the top and bottom plates of the filtering unit by drawing these plates together by means of the winged nut 25. Due to the engagement of the flanges 21b and 22a with the filtering element 26 at the open ends thereof, a seal is effected so that the likelihood of air bypassing the element at its edges without being filtered is minimized.

A second self-supporting cylindrical filtering element 27 located closely adjacent and concentric with the stem 20 is also provided. The element 27 is coated with flock substantially in the same manner as the cylindrical element 26 and has a diameter to fit closely around the central flange 21a of the bottom plate. For the purpose of centralizing it at the top plate, the latter is embossed to provide a downwardly dished center portion 22b closely fitting inside the upper end of the element 27. The meeting ends of the element 27 are joined in a manner similar to that used for the element 26, by a clamp strip 27a having lanced fingers 27b, as shown in Fig. 1.

The invention also provides another novel and self-supporting filtering element 28 in the form of a multi-pointed star which is disposed between the elements 26 and 27 to provide somewhat of a tortuous path for the air passing through the filter unit. The element 28 is of flocked mesh, being shaped by initially zigzag folding it into a pack as shown in Fig. 8, in which form it may be conveniently handled for shipment, replacement, etc. The detail shown in Fig. 9 illustrates the bending of the mesh, as at one of the points of the star. For supporting the star-shaped element 28, a pair of identical spacer rings 29 and 30 are provided, one such ring being illustrated in Fig. 5. Referring to Fig. 2, the bottom and top plates 21 and 22 of the filter have embossed circular beads 21c and 22c respectively, adapted to engage and centralize the spacing rings 29 and 30, the latter having cylindrical flanges 29a and

30a respectively, engaging the inner bends of the star, and also having pluralities of fingers **29b** and **30b** which are lanced from the rings for clamping selected bends of the star to the flanges. As shown in Fig. 1, the meeting ends of the element **28** are overlapped in the manner indicated.

Preferably the star-shaped element **28** is provided with cloth binding strips **28a** and **28b** which are folded over the bottom and top edges respectively. These strips, which may be cemented in place to securely hold them, may function as gaskets in engaging the inner surfaces of the top and bottom plates to prevent the passage of air at these points.

The filtering unit is adapted to be mounted on an air intake pipe by means of the stem **20**, the air supply to flow through the bore of the stem. As shown in Figs. 2 and 3, for this latter purpose the walls of the stem **20** are cut away to provide a pair of oppositely located elongate slots **20a** and **20b** which open into the interior of the element **27**.

By this construction suction applied to the stem **20** will cause air to be sucked through the elements **26**, **28** and **27** consecutively in the order given. As is often customary in air filters, the elements may be coated with a viscous non-drying substance such as lubricating oil, so that the dust-collecting action of the flock is enhanced. According to the invention by the provision of the upturned flanges **21a** and **21b** on the lower plate **21**, the latter may carry a quantity of oil when the filtering unit is mounted with its axis vertical, this oil traveling by capillary attraction up the elements **26**, **27** and **28** and maintaining a dirt-trapping coating or film on the flock. Preferably the size of the mesh of the element **26**, pictured in Fig. 6, is larger than that of the element **28**, and the latter in turn larger than that of the element **27**, pictured in Fig. 7, as an example, the element **26** may be ten mesh, the element **28** fourteen mesh, and the element **27** sixteen mesh. This is advantageous since the speed of the air flow through the element **26** is slower than through the element **28**, and the speed through the element **27** faster than through the element **28**.

The filter elements **26**, **27** and **28** being comparatively rigid, will be adequately supported by the respective associated parts of the housing of the unit, and will not loosen if the unit is subjected to vibrations not greatly in excess of those normally encountered. In connection with this, the reinforcement provided by the cementitious binder at the points where the wires of the mesh cross each other contributes to the mechanical stability and strength.

If, as a result of damage, or clogging of the mesh due to long continued use, it is desired to remove the elements, this may be quickly and conveniently accomplished by loosening the winged nut **25** and removing the top plate **22**. The elements may then be easily lifted out and either cleaned by dipping in cleaning solution, or replaced with new.

If the filter is to be used where it is desirable to have an oil or other viscous coating on the elements, the nature of the cement or adhesive used to secure the flock to the wire should be such that it will not be affected by this coating, nor the cleaning solution employed to remove the coating in cleaning the element.

A modified form of the invention is shown in Fig. 10. According to this form a single self-supporting filtering element **31** of flocked mesh

shaped like a multi-pointed star is mounted between the plates **21** and **22** so that the points of the star engage and are positioned by the flanges **21b** and **22a**. Preferably the top and bottom edges of the mesh of the element **31** are provided with folded cloth binding strips, as in the case of the element **28**, to act as gaskets and prevent by-pass of air without filtering.

By forming the element **31** in the shape of a multi-pointed star, a large surface area is presented for the passage of air, so that the speed of flow is reduced, thereby resulting in a more effective removal of dust, dirt, etc.

In another modified form of the invention, shown in Fig. 11, a plurality of concentric cylindrical flock-coated mesh filtering elements **32**, **33**, **34** and **35** are provided, nested one within another. The outermost element **32** fits closely within the peripheral flanges of the top and bottom plates, the latter only, designated by the character **36**, being shown, with flange **36a**.

For spacing the elements in concentric positions, the bottom and top plates are embossed to provide knobs **37** which are located as shown, engaging the edge portions of the elements and preventing movement of same.

The meeting edges of the cylindrically formed mesh elements are secured together by folding to form interlocked seams **38** which prevent by-pass of air along these edges.

Due to the elements having surface areas which are graduated, the speed of air flow through the respective elements is also graduated, and preferably the size of mesh is chosen accordingly, the outermost element having the largest mesh, and the innermost the smallest.

Also, preferably the end portions of the cylindrical elements are provided with folded cloth binding strips which engage the end plates and function as gaskets.

An air filtering unit adapted for mounting with its axis horizontal is shown in Figs. 12, 13 and 14.

As shown, a housing is provided comprising a pair of circular substantially parallel end plates **39** and **40**, the plates having inwardly extending peripheral flanges **39a** and **40a**, and central inwardly dished portions **39b** and **40b** respectively.

Each plate is centrally apertured to receive a bolt **41** which, by means of a nut **42**, holds the end plates from separating.

A self-supporting cylindrical flocked mesh filtering element **43** is mounted between the plates **39** and **40**, the ends of the element fitting closely about the dished portions **39b** and **40b** for positioning thereby. Engaging the exterior surfaces of the flanges **39a** and **40a** is a self-supporting semi-cylindrical flocked mesh element **44**, the two straight edges **44a** of which (Figs. 13 and 14) are clamped between folded straight edges **45** of a concavo-convex mounting plate **46** which latter also engages the outside surfaces of the flanges and complements the element so that together they form a complete cylinder.

The filtering element **44** and plate **46** are securely clamped to the end-plates **39** and **40** by bands **47** and **48** which may be tightened by bolts **49**, as shown in Fig. 12.

In addition to the cylindrical filtering elements **43** and **44**, a self-supporting star-shaped flocked mesh element **50** is mounted between the end plates, the straight edges **50a** of the element being hooked under the folded inturned edges **45** of the mounting plate.

Referring to Fig. 12, the inner surface of the

end plate 39 is covered or coated with a yielding substance 39c such as rubber, the synthetic Thiokol being for instance suitable, so that when the filtering elements are properly positioned and the end plates 39 and 40 drawn together by the bolt 41, prior to finally tightening the bands 47 and 48, the edge of the star element 50 will be embedded in the rubber and the latter will function as a seal to prevent by-pass of air.

An alternative structure for accomplishing the same result is also shown in Fig. 12, in connection with the end plate 40. A strip of felt 51 is interwoven in the edge of the element 50, so that when the plate 40 is held against the edge the felt will be engaged and seal all openings.

In making up the element 50 for use with felt sealing strips, the mesh might be fabricated in large widths with a wide strip of felt interwoven at regular intervals, and the elements then formed by cutting the mesh along the center lines of the felt strips, so that each edge formed by the cut would have an interwoven felt strip.

In assembling, when the elements 43, 44 and 50 have been mounted between the end plates 39 and 40, the tie bolt 41 is tightened to draw together the plates, which thereby clamp the elements 43 and 50 between them. The bands 47 and 48 are then tightened, securely clamping the mounting plate 46 and element 44 to the end plates.

For the purpose of supporting the filter unit on an air intake pipe of a carburetor or the like, a tubular stem 52 is provided passing radially through the center of the mounting plate 46, which is formed to receive it, and into the cylindrical element 43, the stem being rigidly fastened to the plate. As shown in Fig. 13, the mesh of the element 43 is formed to fit closely to the outside of the stem 52, and may be welded or otherwise fastened to the latter.

The connections between the end plates 39, 40 and the mounting plate 46, and between the latter and the stem 52 are preferably leak-proof so that oil or other viscous liquid may be placed inside the mounting plate to mount by capillary attraction on the filtering element 50.

The self-supporting flock-coated filtering grids of the present invention may be formed of stamped sheet metal, perforated paper, or of wire mesh both metallic or non-metallic. With regard to the latter the mesh may be made of wires of Vinylite or other suitable plastic. Or the grids may be made of expanded metal, expanded paper, papier-maché and the like, depending on the use, in each case the adhesive for securing the flock to the grid being chosen with particular reference to the grid material.

Where comparatively soft materials are used in constructing the filtering grid, the portions of the latter which engage the end plates may de-

form slightly when the plates are drawn together, and conform closely to the plate surfaces, making gaskets unnecessary.

Variations and modifications may be made within the scope of this invention and portions of the improvements may be used without others.

I claim:

An air filtering unit comprising a pair of spaced substantially parallel circular plates each having a pair of circular flanges one at its periphery and the other adjacent its center, extending toward the other plate; a tubular support for the plates, of smaller diameter than the flanges thereof, extending from the center of one plate through the center of the other and rigidly fastened to the latter, the protruding end of the support being adapted to connect to an air intake line, and said support having an aperture opening into the space between the plates for passage of air; a pair of cylindrical grids having the surfaces thereof covered with flock, mounted between the plates, respectively engaging the peripheral and center flanges thereof to be positioned thereby; a pair of rings having flanges mounted against the inner surfaces of the circular plates, said plate having means for positioning the rings centrally of the plates; a zigzag grid covered with flock, mounted between the plates and engaging the flanges to be positioned thereby, said grid extending in a star-shaped path between the cylindrical grids so that air entering the aperture of the support will first pass through the grids consecutively and be filtered thereby; and means demountably fastening said one plate to the support so that the grids may be demounted when the plate is removed.
